(57) **CLAIM**

The ornamental design for a “self-inspection apparatus,” as shown and described.

DESCRIPTION

FIG. 1 is a front perspective view of the self-inspection apparatus;

FIG. 2 is a front view of the self-inspection apparatus;

FIG. 3 is a rear view of the self-inspection apparatus;

FIG. 4 is a right view of the self-inspection apparatus;

FIG. 5 is a left view of the self-inspection apparatus;

FIG. 6 is a top view of the self-inspection apparatus;

FIG. 7 is a bottom view of the self-inspection apparatus; and,

FIG. 8 is a front perspective view of the self-inspection apparatus shown in an environment of a toilet.

The broken lines adjacent the shaded areas represent the bounds of the claimed design while all other broken lines are directed to environment and are for illustrative purposes only; the broken lines form no part of the claimed invention.
